TRASH PAIL COVER

Maurice Lumley, Cincinnati, Ohio, assignor to
 The F. H. Lawson Company, Cincinnati, Ohio,
 a corporation of Ohio

Application September 29, 1941, Serial No. 412,804

7 Claims. (Cl. 220—36)

My invention relates to shells which are placed over trash cans, waste material cans etc. which are open at the bottom for said purpose and are closed when not opened by mechanism which permits of insertion of material being inserted through the shell covers to fall into the trash cans lying within. Such a device is ornamental in shape, and completely covers the can.

In the particular form shown the top of the cover structure is generally of dome shape with a segmental inset at the rear of which is the opening, said opening being closed by a gravity door, hinged above it. The door is operated by a foot treadle on the outside of the shell, and at the side thereof. The problem involved is to provide a strong and simple device for operating the door, not subject to being bent out of shape by careless operation and which can be simply mounted in such a way as not to interfere with placing the shell of the device over a trash can.

In the drawing I have shown a typical structure which will illustrate an example of my invention, the patentable features of which will be set forth in the claims that follow to which reference is hereby made.

In the drawing, Figure 1 is a top plan view of the exemplary device.

Fig. 2 is a front elevation thereof with parts broken away.

Figure 3 is an enlarged section on the line 3—3 of Fig. 2.

Fig. 4 is an enlarged section on the line 4—4 of Fig. 2, being a detailed side elevation of the cover operating levers located in the dome.

Fig. 5 is a view similar to Fig. 4 but showing alternate positions of the levers as occur when lifting the door to open position.

Fig. 6 is an enlarged section on the line 6—6 of Fig. 2.

Fig. 7 is a perspective of the closure door.

Fig. 8 is a perspective detail of the door engaging link.

Fig. 9 is a perspective of the foot pedal lever.

Fig. 10 is a perspective of a disc employed in conjunction with the member of Fig. 9.

The inner container or trash can is indicated in the drawing at 1. The outer cover has, in this instance, a cylindrical shell 2 although some other decorative shape could be used. This shell fits over the trash can with enough space left for the door operating mechanism.

The upper portion of the cover is formed of a dome shaped piece 3 which fits down snugly over the shell 2, which dome shaped piece is cut away segmentally and a casing inserted therein. This

casing has sides 4, 4 which need not be parallel, a bottom 5, and a top 6, which are in each instance suitably flanged and engaged with the dome shape shell except for the bottom 5 which is flanged and shaped to fit over the top of the shell 2. The mode of mounting this casing is not an essential. It may be made of bright metal and the flanges form a decorative border about the opening in the preferred form. The word 5 segmental is used in a general sense, meaning the result of cutting a four sided opening in a hemispherical body. A polygonal angle would be more accurate perhaps.

The back of the casing is closed by a door 7 10 which is hinged at 8 to the top of the inset casing. The side walls of the casing are sloped (see Fig. 4) so that the door hangs by gravity snugly against the sides and bottom of the casing. To insert material into the casing the door is swung 20 inwardly and rearwardly, leaving an access opening through which material inserted will fall into the trash can within.

The mechanism for swinging the door is mounted on one of the sides 4 of the inset casing. 25 This permits of an operating arm being dropped down vertically to the lower end of the wheel for engagement with a foot pedal arm in a position close to the sides of the shell.

A bell crank lever 9 is secured pivotally on 30 the side 4, which is selected. One of the arms of this bell crank is pivotally connected to the operating arm 10 which extends down along the side of the shell, as already indicated. The other end of the arm contacts with one of the arms of another bell crank 11, the upper end of the other arm of which is bent over to form a hook 12. Projecting from the one end of the door at its upper portion is a fixed finger 13 which 35 is bent at 14. The hook 12 engages over this bent finger, and when the bell crank 11 is rocked the hook will cause the door to swing open. This rocking takes place when the operating arm is depressed. This depression rocks the bell 40 crank 9 to lift its free arm, which engages the free arm of the bell crank 11 moving it in an upward direction. This moves the hook rearwardly, and the finger is so oriented and shaped that this rocks the door on its hinged connection. Release of the operating arm permits the 45 door to close by gravity.

As a simple way for connecting up a foot treadle (Fig. 6), I provide a treadle 15 which is mounted on a bent rod 16 that is thrust through 50 a hole 15a in the shell. The rod has integral

therewith a circular disc shape member as indicated at 17, the hole in the shell being of sufficient size to admit it. Also integral with rod 16 and disc 17 is a circular bearing member 17a. Inside of the shell is a bracket 18 welded across the hole 15a which bracket has a circular opening that serves as a bearing for the bearing member 17a.

The bent rod 16 terminates in a threaded portion 19, and the bearing disc has ribs 20 thereon on its inner face on opposite sides of the said threaded portion. A disc 21 having an ear 22 for connection with the operating arm, is slotted as at 23 so that it can be thrust over the threaded end 19 with the slot engaged by the ribs 20 to make a fixed or non-rotary connection, and a nut and washer 24 screwed over the said end 19.

By this arrangement the whole pedal assembly in one piece can be thrust in place, the operating arm pivotally connected by a suitable pin to the ear of the disc, and the disc slipped into place and bolted down by the nut. There is nothing to bend out of shape, a quite adequate bearing is supplied, and the amount of movement of the pedal will be ample to swing the door in the dome of the device open for ready insertion of any waste material.

Having thus described an example of my invention what I claim as new and desire to secure by Letters Patent is:

1. A trash can cover device having a shell open at the bottom for engaging over a trash can, said shell having at its upper portion a closure, a casing inset into the closure, having inwardly sloping edged sides and a bottom portion, a door constituting the rear portion of the casing, means for hinging the door at the top of the said inset casing so as to engage the sides and bottom by gravity, a foot treadle projecting pivotally at the lower portion of the shell, and connections from the foot treadle to the door for opening the door upon movement of the foot pedal, said means including an operating rod extending downwardly through the shell from a position above the top of the enclosed trash can in a position close to the side of the shell so as not to interfere with the positioning and removal of the cover from the trash can.

2. The device according to claim 1 in which the closure at the upper end of the shell is dome shaped, with the casing inset into a generally segmental opening in the dome, said dome being above the level for the trash can.

3. In a trash can covering device the combination with an inset casing having a door at the inner end, means for hinging the door at its upper end so that it closes by gravity, and a lever device for operating the door comprising an arm on the door, a bell crank having its long arm engaging the door arm, another bell crank the short arm of which engages by abutting against the short arm of the first bell crank, and an op-

erating rod connected to the long arm of the second bell crank.

4. In a trash can covering device the combination with an inset casing having a door at the inner end, means for hinging the door at its upper end so that it closes by gravity, and a lever device for operating the door comprising an arm on the door, a bell crank having its long arm engaging the door arm, another bell crank the short arm of which engages by abutting against the short arm of the first bell crank, and an operating rod connected to the long arm of the second bell crank, the engagement of the first bell crank with the arm on the door being effected by a hook on the bell crank.

5. A foot treadle assembly for actuating an access door in a trash receptacle or the like, comprising a bracket within the receptacle having a bearing therein, a treadle, an arm fast on the treadle arranged to fit into the bearing, said receptacle having a hole for insertion of the arm which carries a bearing member, a rocker plate mounted on said bearing member having connection for an access door operating rod, and threaded means for mounting the plate on the inner end of the arm beyond said bearing, the plate and bearing having key and slot engagement.

6. A foot treadle assembly for actuating an access door in a trash receptacle or the like, comprising a bracket within the receptacle having a bearing therein, a treadle, an arm fast on the treadle arranged to fit into the bearing, said receptacle having a hole for insertion of the arm which carries a bearing member, a rocker plate mounted on said bearing member having connection for an access door operating rod, and threaded means for mounting the plate on the inner end of the arm beyond said bearing, the plate and bearing having key and slot engagement, said threaded means comprising threads on the end of the foot treadle arm, and a nut for engaging said threaded end to hold the plate against the bearing member on said arm.

7. A foot treadle assembly for actuating an access door in a trash receptacle or the like, comprising a bracket within the receptacle having a bearing therein, a treadle, an arm fast on the treadle arranged to fit into the bearing, said receptacle having a hole for insertion of the arm which carries a bearing member, a rocker plate mounted on said bearing member having connection for an access door operating rod, and threaded means for non-rotatably mounting the plate on the inner end of the arm beyond said bearing, said threaded means comprising threads on the end of the foot treadle arm, and a nut for engaging said threaded end to hold the plate against the bearing member on said arm, said bearing member having key means to engage slotted means in the plate.

MAURICE LUMLEY.
